(57) **CLAIM**

The ornamental design for a container lid, as shown and described.

DESCRIPTION

FIG. 1 is a perspective view of a container lid showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a perspective view of FIG. 1.

The broken lines are shown for the purpose of illustrating both parts of the article as well as environmental subject matter of an exemplary container and exemplary container contents. None of the broken lines form part of the claimed design.

1 Claim, 5 Drawing Sheets(56)
